UNITED STATES PATENT OFFICE.

GEORGE TURNER, OF LANSING, MICHIGAN.

IMPROVEMENT IN GATE AND DOOR CLOSING DEVICE.

Specification forming part of Letters Patent No. 41,948, dated March 15, 1864.

To all whom it may concern:

Be it known that I, GEORGE TURNER, of Lansing, in the county of Ingham and State of Michigan, have invented a new and Improved Gate and Door Closing Device; and I do hereby declare that the following is a full, clear, and exact description of the same, reference being had to the accompanying drawings, making a part of this specification, in which—

Figure 1 is a perspective view of my invention. Fig. 2 is a plan or top view of the same. Fig. 3 is a diagram showing the application of the invention to either a right or left hand gate.

Similar letters of reference indicate corresponding parts in the several figures.

The invention relates to an improvement in the old and well-known weight-and-pulley attachment for closing doors, and is also designed to supersede the ordinary weight-and-chain attachment for closing gates.

The invention consists in the employment or use of a fixed and a self-adjusting pulley arranged in such a manner that the device may be applied to either a right or a left hand door or gate, and operate equally well in either application without the liability of the cord slipping from the pulleys in any position of the door or gate, the weight at the same time being entirely out of the way.

To enable those skilled in the art to fully understand and construct my invention, I will proceed to describe it.

A represents an arm, which may be of cast-iron, and having at one end two plates, *a a*, which are at right angles with each other, said plates having holes in them, through which screws pass to secure the arm A to the angle of the door or gate-post B, as will be understood by referring to Fig. 3.

At the outer or opposite end of the arm A there is a vertical fixed pulley, C, the axis *b* of which has its bearings in pendants *c c*, so that the upper surface of the pulley C will be below the top of the arm, as shown clearly in Fig. 1.

To the outer end of the arm A there is attached by a pivot-bolt, *d*, a plate, D, which is allowed to work on the bolt *d* a certain distance, either to the right or left, as will be understood by referring to Fig. 2, in which the plate D is shown in one position in black and in

the other in red. This movement of the plate D is limited by means of shoulders *e* at the under side of the arm A, and similar shoulders, *f*, at the under side of the plate D. (See Fig. 1 and dotted lines in Fig. 2.)

At the under side of the front part of the plate D there is a horizontal pulley, E, which is fitted loosely on a vertical pendent axis, *g*, attached to plate D. The periphery of the pulleys E and C are of concave form, and the center of the periphery of the pulley E is in line, or nearly so, with the center of the upper part of the periphery of the pulley C, so that the rope or cord (shown in red) which passes over the pulley C will pass in a horizontal line around the pulley E, as shown in red in Fig. 1.

The arm is secured by screws or bolts to the post to which the door or gate is hung, said arm projecting angularly from the post at the door or gate side, in consequence of the plates *a a* abutting against two adjoining sides of it, as shown in Fig. 3. The rope or cord is attached to the door or gate at about one-third the distance of its width from its free or unhinged end.

From the above description it will be seen that as the door or gate is opened and closed the weight will rise and fall by the side of the post to which the arm A is attached, and to which the door or gate is hung, the pulley E serving as a guide to keep the cord or rope properly on C. The pivoted plate D admits of the arm A being attached to the post of either a right or left hand door or gate, as will be seen by referring to Fig. 3, in which the arm A is shown in red attached to an opposite post. By this adjustment of the plate D the pulley E, which is attached to it, is allowed to adjust itself in line with the fixed pulley C when the arm A is attached to either post.

By this arrangement the weight is entirely out of the way, and is far preferable to the swinging chain and weight hitherto applied to gates, as the latter arrangement is frequently in the way, and the weight has a very unequal action on the gate. My invention may also be advantageously applied to doors when a weight is preferred to a spring for closing them.

The pulleys C E, in consequence of being

below or underneath the arm A and plate D, are fully protected from snow and ice in winter.

Having thus described my invention, what I claim as new, and desire to secure by Letters Patent, is—

A pulley device for the weight, cord, or rope of doors and gates, composed of an arm, A, with a fixed vertical pulley, C, attached, in

combination with an adjustable plate, D, pivoted to A and having a horizontal pulley, E, fitted to it, all arranged to operate in the manner substantially as and for the purpose herein set forth.

GEORGE TURNER.
